UNITED STATES PATENT OFFICE.

JAMES FOSTER KING, OF GLASGOW, SCOTLAND.

CONSTRUCTION OF SHIPS.

1,391,389.

Specification of Letters Patent. Patented Sept. 20, 1921.

Application filed October 6, 1920. Serial No. 415,154.

To all whom it may concern:

Be it known that I, JAMES FOSTER KING, a subject of the King of Great Britain and Ireland, and a resident of the city and county 5 of Glasgow, Scotland, have invented certain new and useful Improvements in the Construction of Ships, of which the following is the specification.

The invention has for its object to take 10 advantage of the close spacing of transverse bulkheads in oil tank vessels, which bulkheads give all the transverse strength required, and by so doing to reduce considerably the scantlings of the ordinary trans- 15 verse frames and floors—the latter being preferably entirely dispensed with—so that they are practically negligible for transverse strength, the stress on the bottom and sides of the vessel being taken up entirely by 20 longitudinal girders of exceptional depth fitted from bulkhead to bulkhead.

The longitudinal web frames or girders may be slotted over the transverse frames, or they may be fitted with a continuous shell 25 connection and the transverse frames connected to the girders by ordinary methods, or to each other by means of joint pieces which pass through the girders.

Two accompanying sheets of explanatory 30 drawings are hereunto appended in which Figures 1 and 2 are half transverse sections and Fig. 3 a longitudinal section of parts of a ship sufficient to show an example of the improved construction.

35 As shown in the drawings a number of longitudinal web frames or girders A are fitted over the whole girth of the hull below the lowest deck or tier of beams. These longitudinal frames are restrained from tripping under stress by angle stays C, and they 40 are held in place by angle bars E and bracket connections G. They are also secured at the ends to closely spaced transverse bulkheads D by means of bulkhead stiffeners J, the 45 angle connections E and brackets H. Between these bulkheads D there are fitted a number of relatively small transverse frames B secured to the longitudinal frames A by the bracket connections G and at the ends 50 by brackets F. The longitudinal web frames A are in this example slotted over the trans- 55

sions of vessels and sizes of tanks or holds therein, and also with heights to which oil or other cargoes rise, and with test head required.

The following scantlings for instance would apply in the foregoing specification 60 to a vessel whose dimensions are 430' x 57' x 34' 6" with an oil cargo:—

Girders A, bottom 60" x .46" spaced 7 feet; sides 48" x .42" spaced 8 feet.

Transverse frames B, 8 $\frac{1}{2}$ " x 3 $\frac{1}{2}$ " x .46" 65 bulb angle spaced 28 $\frac{1}{2}$ ".

Angle stays C, 6" x 3 $\frac{1}{2}$ " x .38" every 4th frame.

Transverse bulkhead D, .48" bottom to .3" top. 70

Longitudinal bulkhead, .52" bottom to 28" top.

Angle bars E, 6" x 6" x .54".

Small brackets F, .38" thick.

Bracket connections G, 8" x 3 $\frac{1}{2}$ " x .38". 75

Brackets H, 54" sided.

Center line bulkhead stiffeners J, 7" x 3" x .36" bulb angle spaced 28 $\frac{1}{2}$ ".

Transverse bulkhead stiffeners 9" x 3" x .44" bulb angle spaced 28 $\frac{1}{2}$. 80

What I claim is:—

1. An oil-tank ship comprising in combination, a hull, a plurality of exceptionally large widely spaced longitudinal web frames arranged over the girth of the hull below the 85 lowest deck or tier of beams, and a plurality of relatively small longitudinally-spaced transverse frames shaped to conform to the contour of the ship and connected to said longitudinal web frames, whereby floors or 90 their equivalent wide spaced bottom transverses may be dispensed with.

2. An oil-tank ship comprising in combination, a hull, a plurality of transverse bulkheads, a plurality of exceptionally deep 95 widely spaced longitudinal girders arranged over the girth of the hull and connected to said bulkheads, and a plurality of relatively small transverse frames shaped to conform to the contour of the ship, arranged intermediate between said bulkheads and connected to said longitudinal girders, whereby 100 floors or their equivalent wide spaced bottom transverses may be dispensed with.

In testimony whereof I have signed my 105 name to this specification.

JAMES FOSTER KING.

The scantlings of the structural members described above will vary with the dimen-
